CLAIM

The ornamental design for an air drum set, as shown and described.

DESCRIPTION

FIG. 1 is a front, top perspective view of an air drum set, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 an enlarged view of the portion taken at line-9 in FIG. 1;

FIG. 10 an enlarged view of the portion taken at line-10 in FIG. 1; and,

FIG. 11 an enlarged view of the portion taken at line-11 in FIG. 3.

The dashed lines in the figures illustrate portions of the air drum set that form no part of the claimed design. The dash dot dash lines in FIGS. 1, 3, 9, 10 and 11 are for the purpose of illustrating the enlarged view indicators and form no part of the claimed design.
